UNITED STATES PATENT OFFICE.

JOSEPH V. HULL, OF BROOKLYN, NEW YORK, ASSIGNOR TO ANCHOR CAP & CLOSURE CORPORATION, OF BROOKLYN, NEW YORK, A CORPORATION OF NEW YORK.

PROCESS FOR SEALING.

1,208,970.

Specification of Letters Patent. Patented Dec. 19, 1916.

Original application filed March 16, 1912, Serial No. 682,051. Patent No. 1,134,065, dated March 30, 1915.
Divided and this application filed February 25, 1915. Serial No. 10,512.

To all whom it may concern:

Be it known that I, JOSEPH V. HULL, a citizen of the United States, residing at Brooklyn, in the county of Kings and State 5 of New York, have invented new and useful Improvements in Processes for Sealing, of which the following is a specification.

This invention relates to a method of forming closures which are applied to containers in which are to be sealed foodstuffs and the like, and has particular reference to a closure of the side sealing type which usually includes a metallic closure having an annular beading in which a compressible 15 gasket is located, the beading and gasket being compressed by suitable means against the side wall of the container to form a seal.

The application is a divisional one, being formed from my co-pending application Serial No. 682,051, issued March 30, 1915, as Patent No. 1,134,065.

One object of the invention is to provide a more efficient method of applying closures to containers for the packing and preservation 25 of foodstuffs; a method in which the closure may be applied quickly to the container without causing breakage of the latter, in which the closure will offer a minimum resistance to the sealing operation, and 30 in which the closure will maintain a hermetic seal for a long period of time; and still another object is to provide a method of sealing which will not unduly strain or break the lacquer upon the closure, or cause 35 the closure to present a wrinkled appearance.

Referring to the drawings: The figure is a sectional elevation of the sealing mechanism disclosed in my co-pending application, Serial No. 682,051 and illustrates my improved sealing method.

The glass or rigid wall container is indicated at 10; the closure of metal is shown at 11 and is equipped with a beading which 45 is indicated at 12, 13 and 14. Within the beading is a gasket 15 formed of rubber or other suitable composition. In the former method of sealing the closure to the container, as shown in my Patent No. 874,201 of 50 December 17, 1907, the top and bottom walls 12 and 14 of the beading were deformed, the wall 13 being under compression at the same time, and the gasket material 15 was squeezed laterally against the glass wall of

the container 10 to effect the seal. In the 55 practice of this method, it has been found that considerable power is required to effect the seal, the metal beading of the cap often becomes wrinkled in radial lines, and the protective coating of lacquer is injured. 60 Apparently this is due to the lack of compressibility of the metal of the beading as compared with the gasket. When the beading is compressed, the cross-sectional area is 65 reduced. The rubber adapts itself readily to the change, but the metal of the beading tends to maintain the same superficial area that it had before the compression.

By my improved method I provide a groove in the beading adapted to receive the 70 excess metal due to the reduction in size of the beading. The arrangement provides for subjecting the entire beading to compression, reducing the cross-sectional area of the beading with relation to the gasket, without 75 at the same time requiring or forcing any substantial reduction in the perimeter dimension of the beading. Under this method of the sealing, the excess metal or a substantial part of it is taken up by or flows 80 into the groove as the pressure of the dies is applied, the beading is reduced as desired without causing any wrinkling or buckling 85 of the metal such as occurs in sealing in the manner previously practised, and in addition the skin of lacquer upon the metal is not broken or seriously injured.

As shown in the view, the groove is formed in the present instance at 20 in the upper wall 12 of the beading, and the anvil 21 is 90 equipped with an annular projection 22 by which the groove may be formed. In the machine shown as disclosing the process, the anvil 21 is stationary, the sectional jaws 23 are drawn upward by suitable means, compressing or deforming the beading between 95 the lugs 24 on the jaws 23 and the anvil 21.

While the groove is shown upon the upper surface of the beading, it is obvious that it may be located at any desired place in the 100 beading and perform the same function; also that the form of beading itself may be altered without departing from the spirit and scope of the invention. The invention also is not limited to the particular manner 105 of forming the groove which is shown.

I claim:

1. The method of sealing a metallic cap

- having an annular beading and gasket to a rigid wall container which consists in placing the cap upon the container compressing the beading in a vertical direction whereby a seal against the side wall of the container, 20 and excess metal of the beading due to its reduction in size is taken care of by the said groove.
6. The gasket material is squeezed laterally from the beading to effect a seal against the side wall of the container, and causing the excess metal of the beading due to its reduction in size upon compression to flow 10 into the form of an annular groove in one of the walls of the beading.
2. The method of sealing a metallic cap having an annular beading and gasket to a rigid wall container which consists in placing the cap upon the container forming a groove in one of the walls of the beading and compressing the beading in a vertical direction, whereby the gasket material is 15 squeezed laterally from the beading to effect a seal against the side wall of the container, 25 and excess metal of the beading due to its reduction in size is taken care of by the said groove.
3. The method of sealing a metallic cap having an annular beading and gasket to a rigid wall container which consists in placing the cap upon the container, deforming the beading whereby the gasket material is moved from the beading to effect a seal against the side wall of the container, and 30 causing excess metal of the beading due to its reduction in size to be taken up in an annular groove in the beading.

JOSEPH V. HULL.
